UNITED STATES PATENT OFFICE.

WILLIAM BLOOMBERG, OF NEW YORK, N. Y.

SUSPENDER-END.

SPECIFICATION forming part of Letters Patent No. 354,673, dated December 21, 1886.

Application filed April 17, 1886. Serial No. 199,192. (No model.)

To all whom it may concern:

Be it known that I, WILLIAM BLOOMBERG, of the city, county, and State of New York, have invented a new and Improved Suspender-
5 End, of which the following is a full, clear, and exact description.

My invention relates to a leather suspender-end; and it consists in cutting the same into strands and braiding or plaiting the strands, 10 which not only renders the end more attractive in appearance, but makes it pliable edge-wise and elastic.

Reference is to be had to the accompanying drawings, forming part of this specification, in 15 which similar letters of reference indicate corresponding parts in both the figures.

Figure 1 is a view of a complete suspender-end made in accordance with my invention, and Fig. 2 is a plan view of the end-blank before plaiting.

In forming the ends A, I stamp out of leather or other suitable material the blank B. This is formed with the solid lower portion, b, in which the button-hole c is formed. Above the 25 button-hole the blank is cut to form several strands, a a, which are braided or plaited to-

gether, as shown in Fig. 1. The ends thus formed are secured in the top leather, d, in the usual manner. The drawers suspender-end C is made like the end A, but with a less number of strands and without a button-hole, the solid portion e being at the upper end, where it is secured in the top leather, d.

By forming the ends as described they are cheap, strong, and elastic, and pliable in all 35 directions, and present a unique and handsome appearance.

Having thus described my invention, I claim as new and desire to secure by Letters Patent—

1. As an improved article of manufacture, 40 a suspender-end made of a solid portion, b, and strands a, connected with the solid portion and plaited together, forming a flat end, substantially as shown and described.

2. The blank B, for a suspender-end, composed of the solid button-hole portion b and strands a, continuous of the solid portion, substantially as described.

WILLIAM BLOOMBERG.
